UNITED STATES PATENT OFFICE.

JOSEPH A. GROEBLI, OF NEW YORK, N. Y.

SEPARATOR FOR BEAD-SEWING MACHINES.

Application filed January 9, 1924. Serial No. 685,084.

To all whom it may concern:

Be it known that I, JOSEPH A. GROEBLI, a citizen of the United States, and a resident of the city, county, and State of New York, have invented certain new and useful Improvements in Separators for Bead-Sewing Machines, of which the following is a specification.

My invention relates to an improvement in the bead separating mechanism for bead sewing machines, by means of which beads loosely strung upon a thread are fed along it and attached to a fabric, either by the same thread or by a second thread; and my improvements are directed particularly to novel features in the means whereby the beads are finally released one by one and allowed to slide down along the thread to the fabric to which they are to be attached; the object of my present improvement being to provide means whereby the feeding of the beads may be arrested, suspended or resumed optionally without interfering with the forward movement of the thread upon which they are strung, thus permitting the machine to be used either as a bead sewing machine or as a plain sewing machine, as the work progresses, according to the wishes of the operator. A machine of this general type is shown in my Letters Patent No. 1,445,764, dated February 20th, 1923; and the application of my present improvements will be readily understood if reference is made to my aforesaid patent for an illustration of the operative mechanism not shown in the drawings of this application.

The separator mechanism whereby the beads are alternately gripped or released in the normal, continuous feeding of the beads is the subject of another application heretofore filed by me in the Patent Office, and now pending Serial No. 651,769, filed July 16th, 1923; and, therefore, I will not describe it further than is requisite for a proper understanding of my present improvements.

In the drawings, Fig. 1 is a side elevation of part of the head of a sewing machine, showing the manner in which my improvements may be connected with and embodied in pre-existing mechanisms; Fig. 2 is an elevation of my improved bead separator associated with a looper and needle; Fig. 3 is a view of the same taken as look-

ing to the left on Fig. 2; Fig. 4 is a view of the same taken as looking in a reverse position from that of Fig. 2, the thread guide and needle being omitted; Fig. 5 is a view of the separator mechanism, looking up on Fig. 2, the thread guide being omitted; Fig. 6 is a cross sectional view, taken on the line 6—6 of Fig. 1, looking down; and Fig. 7 is a vertical sectional view, showing the parts in the same positions as in Fig. 2.

In all the figures similar parts are designated by similar reference numerals.

A bead separator is carried by a tube 53 which corresponds to the tube 53 of my aforesaid Patent No. 1,445,764, and may be mounted and rotated by similar mechanism. The looper arm 48 is carried by a collar or head 46 attached to a tube 38, which corresponds to the tube 38 in my aforesaid patent and may be mounted and rotated by similar means, while the needle 75 and the feeder foot 106 correspond to the parts similarly numbered in my said patent.

In separators, of the class to which my improvements are directed, the beads are dropped one by one so as to fall at the right time into proper position for being secured to the fabric by the stitching mechanism, the operation of the separating mechanism being continuous, a bead or beads, for instance, being passed by the separator for each cycle of operation of the stitch mechanism. But under certain circumstances it becomes desirable to hold back, optionally, the beads, while allowing the stitch mechanism to continue to function, so that the machine may be employed for bead sewing or for plain sewing according to the wishes of the operator.

A separator embodying bead gripping and releasing elements which open and close to separate and drop the beads, substantially as shown in the drawings herein, is the subject of a separate, pending application by me for a United States patent Serial No. 651,769, filed July 16th, 1923. I will, therefore, not describe the details of that part of the construction of the separator further than is necessary for a clear understanding of my present improvements.

The lower end of the bore of tube 53 is contracted and deflected to open through

the side of the tube at 2; and a yoke-like member 4 is pivoted, by screws 5, 5, to the tube 53, the yoke being provided with an upwardly projecting arm 6, passing through a slot 7, in a guide plate 8 carried by the tube 53, the yoke 4 also being provided with a downwardly depending arm 9, secured thereto by suitable means, such as screws 10, 10, so that it will rock back and forth with the movements of the yoke 4 on its pivots.

The lower end 11 of the arm 9 lies transversely below the end of the tube 53, and is so proportioned that it may be rocked to one side under the end of the tube, so as to lie beneath the bead duct and at approximately the distance of one bead length beneath it, but may be rocked in the opposite direction so as to clear the bead duct, and allow the bead to drop, it being so formed as to clear the needle when it is so rocked. By providing the arm 9 with slots 13, 13, through which pass the securing screws 10, 10, vertical adjustment may be obtained so as to accommodate its position to beads of different lengths.

A spring 15 interposed between a support 16, attached to the lower end of the tube 53, and the yoke 4, presses the bow of the yoke 4 and its arm 6 upward, yieldably.

To the looper tube 38 is secured a cam race 20 which rotates with the looper tube. The arm 6 travels against this cam race; and the yoke 4 will be rocked to and fro by the cam race 20 once with each revolution of the looper tube 38.

A jaw member 25 is pivoted, as at 26, in a bearing 27 carried by the lower end of the tube 53; and it is provided with an arm 28 which registers in the lower part of the bead duct 2, being normally kept to duty by a spring 30, the ends of which are held in the support 16, while the loop of the spring lies behind the jaw 25. The inner face of the arm 28 is disposed at an acute angle to the opposed face of the bead duct 2, so that the arm 25 will engage the lowermost bead laterally, but, preferably, will not bear against the beads higher up.

The jaw 25 is provided with a laterally disposed arm 31, which is engageable by the end 32, of an arm 33, pivoted at 34 to an extension 35 secured to the yoke 4, as by screws 36, 37, so that the arm 33 swings back and forth with the yoke 4.

A spring 38, interposed between the yoke 4 and the pivoted arm 33, normally keeps the arm depressed, in the position shown in Figs. 3, 4 and 5; so that its shoulder 39 rests against a plate 40, pivoted, as by means of a screw 41, passing loosely through a lug on the plate 40 and into the support 16, and guided by another screw 42, also passing loosely through the plate 40 and into the support 16, so that the plate may swing to-

ward or away from the support, the normal position of the plate for bead sewing being that shown in Figs. 2, 3, 4 and 5.

A wire 45, headed below, and passing freely through a hole in the plate 40, is carried up through the tube 53 to a suitable point from which it may be carried out through the side of the tube and connected with means whereby it may be raised and lowered.

Such means are shown in the drawings as consisting of a collar 56, surrounding the tube and engaged by one end 47 of a bell crank 44, pivoted in a suitable bearing in the head of the machine. From the opposite arm of the bell crank, a rod 49 is carried down to a control lever 50, pivoted on the head of the machine and provided with means, such as a cam 51, preferably provided with stops 52, 53, by the movement of which cam the rod 49 may be raised and lowered, to rock the bell crank 44, and thereby to raise and lower the wire 45. A spring 54, between the bell crank and machine head, keeps the rod 49 in duty on the cam 51.

When the rod 45 is lowered in the tube 53, the plate 40 drops down into the position shown in Figs. 1 to 5 inclusive; and, as the cam race 20 is carried around by the looper tube 38, in the operation of the machine, and the yoke is rocked, to and fro, it will, through the arm 33 engaging with the arm 31 on the member 25, rock that member so as to alternately open and close the opening of the bead channel; engaging, when closed, the lowermost bead and releasing it, when opened, to drop down to the arm 11 by which it will be released by the reverse movement of that arm.

But, if the wire 45 is raised, as by means of the hand control 50, the plate 40 will be drawn up toward the bottom of the support 16, pushing up the arm 33 so that its end 32 will lie above the opposed end 31 of the member 25, so that, when the arm 33 is rocked back and forth with the yoke 4, the arm 31 will lie out of contact with the end 32, and will not be affected by its movement, but will remain closed, arresting the downward movement of the beads, and permitting the machine to be used for ordinary machine stitching, the bead thread being drawn down, through the loosely strung beads, to the needle as required by the stitching.

By reversing the position of the hand control, the separator may be released to function for bead sewing purposes.

It will be seen, therefore, that by means of my improvements I produce a machine on which either ordinary stitching or bead sewing may be done, according to the wishes of the operator and the requirements of the work in hand, the bead sewing elements be-

ing thrown into or out of operation by the simple manipulation of the hand control.

While I have illustrated my improvements as applied to a two thread machine, it is obvious that they are also applicable to a single thread machine, employing a bead thread upon which beads are loosely strung so that the thread may be drawn forward through the beads to the stitch forming mechanism.

It will also be understood that the mechanism shown is to be considered as an illustrative and not as an exclusive type. For details of construction may be varied by the use of mechanical equivalents or the like without departing from the spirit of my invention as described and claimed.

Having thus described my invention, what I claim and desire to secure by Letters Patent of the United States, is:—

1. The combination, in a sewing machine, of stitch-forming mechanism means for supplying a thread with beads loosely strung thereupon, bead separating means, and optionally operable means for superseding the operation of the separating means.

2. The combination, in a sewing machine, of stitch-forming mechanism means for supplying a thread with beads loosely strung thereupon, a bead separator embodying bead holding and bead releasing means, and optionally operable means for suspending the releasing action of the separator.

3. The combination, in a sewing machine, of stitch-forming means, means for supplying a thread with beads loosely strung thereupon automatically operable, means for holding and releasing the beads successively, and optionally operable means, independent of said automatically operable means, for suspending the releasing action of the holding and releasing means.

4. The combination, in a sewing machine of stitch-forming means, means for supply-

ing a thread with beads loosely strung thereupon automatically operable, means, embodying bead gripping elements, for holding and releasing the beads successively, and optionally operable means, independent of said automatically operable means, for suspending the releasing action of the gripping element.

5. The combination, in a sewing machine, of stitch-forming mechanism, bead separating means, embodying bead supporting means automatic operating mechanism therefor, and bead gripping and releasing means, of optionally operable means independent of the automatic operating mechanism for suspending the releasing function of the said gripping means.

6. The combination, in a sewing machine, of stitch-forming mechanism, a bead separator embodying reciprocable bead holding and releasing means automatic operating mechanism therefor, and optionally operable means independent of the automatic operating mechanism for suspending the releasing action of the separator.

7. The combination, in a sewing machine, of stitch-forming mechanism, a bead separator embodying reciprocable bead holding and releasing means, automatic operating mechanism therefor, and optionally operable means independent of the automatic operating means and provided with locking means for suspending the releasing action of the separator.

8. The combination, in a sewing machine, of stitch-forming mechanism, an automatically operable bead separator embodying reciprocable bead holding and releasing means, and optionally operable means provided with locking means embracing a pivoted latch for suspending the releasing action of the separator independently of said automatically operable means.

JOSEPH A. GROEBLI.
